United States Patent Office

Des. 218,223
Patented Aug. 4, 1970

218,223

PACKAGE OR SIMILAR ARTICLE

Keith Stewart Carmichael, Wilmington, Del., assignor to
E. I. du Pont de Nemours and Company, Wilmington,
Del., a corporation of Delaware

Filed Nov. 12, 1968, Ser. No. 14,376

Term of patent 7 years

Int. Cl. D9—99

U.S. Cl. D9—184

The figure is a perspective view of a package or similar article showing my new design.

The end and side not shown are identical to that shown, while the bottom is plain with the individual cartons visible through the transparent film.

I claim:

The ornamental design for a package or similar article, substantially as shown and described.
